PHASE MODULATION DETECTOR CIRCUITS

Murray G. Crosby, Riverhead, N. Y., assignor to
Radio Corporation of America, a corporation of
Delaware

Application June 10, 1942, Serial No. 446,427

7 Claims. (Cl. 250—27)

My present invention relates to phase modulation receivers, and more particularly to improved and simplified forms of detectors of phase modulated (PM) carrier waves.

I have disclosed and claimed various types of phase modulation detector circuits of the filtered carrier type in my U. S. Patent No. 2,081,588, granted May 25, 1937; U. S. Patent No. 2,065,565, granted December 29, 1936, and U. S. Patent No. 2,063,588, granted December 8, 1936. Generally, in those circuits the phase modulated wave energy is subjected to a filtering step in order to remove the modulation side bands from the wave energy, the filtered carrier energy being combined with the unfiltered PM wave energy to secure detection. However, these prior receiver circuits were somewhat complicated. In the various detection circuits described herein simplified and efficient arrangements are secured.

It may be stated that it is one of the main objects of my present invention to provide PM detectors in which three, or four, electrode crystal filters may be utilized to provide a filtered carrier; the filtered carrier being given a 90 degrees phase shift and recombined with the unfiltered PM energy in a detector so as to derive the modulation signals which were originally applied to the carrier at the PM transmitter.

Another object of my invention is to utilize in a PM detector circuit a crystal filter for providing carrier energy free of any modulation side band components, and the rectification of combined filtered carrier energy and unfiltered PM wave energy being performed by any one of various devices.

Still other objects of this invention are to improve generally the simplicity and efficiency of PM detector devices, and more especially to provide PM receivers which embody detectors of the aforesaid type which are reliable in operation and economical to manufacture and assemble.

The novel features which I believe to be characteristic of my invention are set forth with particularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings:

Fig. 1 schematically shows a PM receiver embodying the present invention.

Figs. 2a to 2d respectively show the manner

in which the detector network of the present invention functions.

Fig. 3 illustrates a modified form of the invention.

Fig. 4 illustrates a further modification of the invention.

Referring now to the accompanying drawings, wherein like reference characters in the different figures designate similar circuit elements, the receiver of Fig. 1 is of the superheterodyne type. This type of receiver is universally employed in the reception of PM wave energy or frequency modulated (FM) carrier wave energy. The carrier frequency of received PM wave energy may be located in any band of ultra-high frequency, and it will be understood that the transmission channel width may be of any desired value. As is well known to those skilled in the art, at the transmitter the phase of the carrier energy is varied in accordance with the amplitude of the modulation signals. Unlike frequency modulation wherein the carrier frequency is deviated in accordance with the amplitude of the modulation signal frequencies, in PM transmission the rate of mean, or center, frequency deviation at the transmitter is greater at the higher modulation frequencies. The receiver networks prior to the demodulator network are conventional in form as shown in Fig. 1. The usual signal collector 10 feeds the collected PM wave energy to a radio frequency amplifier adapted to be tuned to the ultra-high frequency carrier of the desired PM wave energy.

The amplified PM wave energy is supplied to a first detector network; locally produced oscillations are provided from a local oscillator. The local oscillations and the collected PM wave energy are heterodyned in a suitable first detector, the resultant heterodyne energy being of intermediate frequency (I. F.). The I. F. energy is amplified in one or more stages of I. F. amplification. The numeral 1 designates the usual I. F. output transformer which feeds the demodulator network. It will be understood that 15 each of the primary and secondary circuits of transformer 1 is tuned to the predetermined operating I. F. value. A resistor is shown connected across the resonant primary circuit of transformer 1 so as to provide a pass band width sufficiently broad to pass substantially all the components of the desired PM channel.

The amplified PM energy developed across the secondary circuit 1' of transformer 1 is applied to the input electrodes 5 and 6 of piezo-electric crystal 2. The opposite end of the piezo-electric

crystal 2 is located between a pair of spaced crystal output electrodes 4 and 3. As shown in Fig. 1 the holders, or input electrodes, 5 and 6 are connected to the opposite sides of the resonant input circuit 1'. The crystal output electrodes 4 and 3 are connected respectively to the anodes 12' and 13' of diode rectifiers 12 and 13.

The cathodes of the diodes 12 and 13 are connected together by series-connected resistors 14 and 15. Each of these resistors is bypassed by a suitable condenser for I. F. currents, and the cathode of diode 13 is grounded. Anodes 12' and 13' are also connected by a second pair of series-connected resistors 9 and 10. The junction of resistors 9 and 10 is connected by an adjustable resistor 11 to the junction of resistors 14 and 15. The high potential side of input circuit 1' is connected to the junction of resistors 9 and 10 through a path consisting of the condenser 17 and adjustable resistor 8 arranged in series. The electrostatic shield 1, shown by the dotted line, is connected to the ground side of the input circuit 1', the shield element 1 acting electrostatically to shield the input electrodes 5-6 from the output electrodes 4-3. The modulation voltage is taken off from the cathode end of resistor 14, and the modulation voltage may be applied to the input terminals of a modulation voltage amplifier.

Automatic frequency control (AFC) voltage is derived from the cathode end of resistor 14. This AFC voltage is utilized to control the reactive effect of a frequency control tube. Those skilled in the art are fully aware of the manner of providing the AFC action. It is sufficient for the purposes of this application to point out that the frequency control tube has its circuits connected to the tank circuit of the oscillator so as to provide a simulated reactance across the tank circuit. The gain of the reactance tube is varied by the AFC bias applied over lead 16, the AFC line including the filter network 16' which prevents pulsating voltage components from affecting the reactance tube. As is well understood, any shift in the mean frequency of the I. F. energy relative to the predetermined I. F. value of the input circuit 1' results in production of AFC bias changes of a polarity and magnitude such as to vary the frequency control tube in a sense to compensate for the aforesaid mean frequency shift.

The crystal holder shown in the demodulator network is of a type more completely described in my aforesaid U. S. Patent No. 2,065,565. The output electrode 4 feeds filtered carrier energy directly to diode 12, while the output electrode 3 feeds filtered carrier energy of opposite phase directly to diode 13. There is fed through the path comprising the blocking condenser 17 and variable resistor 8 unfiltered PM wave energy. This unfiltered energy is combined with the filtered carrier energy in resistor network 9-10-11. Thus, it will be seen that one diode receives a combination of filtered and unfiltered wave energy, while the other diode receives the same combination of energies but with a 180 degrees phase reversal on the filtered carrier. This phase reversal is caused by the fact that the electrode 3 is on the opposite side of the crystal from electrode 4. It has been experimentally confirmed that this phase reversal exists.

Attention is now directed to Figs. 2a to 2d inclusive, since the latter graphically explain the manner in which the input network of the demodulator functions. In Fig. 1 the reference "PM converter" is applied above the demodulator input network to indicate that the function of

the input network is to convert the applied PM wave energy to amplitude modulated (AM) wave energy. The operation of the demodulator depends upon the combining of filtered PM carrier with unfiltered PM wave energy with such a phase relation that a carrier is provided which is combined with the side bands to form AM wave energy. The latter is readily rectified by the opposed diode rectifiers 12 and 13.

Referring to Figs. 2a and 2b, they show the normal side band relations of an AM wave and a PM wave respectively. In these figures C is the carrier vector, while S_1 and S_2 are the side band vectors. The combination of energies effected by the PM converter network at the diode 12, for example, is represented in Fig. 2c. It will be noted from this figure that the filtered PM carrier, which is represented by C' , is phase shifted 90 degrees with respect to the unfiltered carrier C. The combination of the filtered carrier C' and the side bands S_1 and S_2 form an amplitude modulated wave as shown in Fig. 2a. The presence of the original carrier C tends to make the resulting combination wave a combination of phase and amplitude modulation. However, since there is an amplitude modulation component present, it may be detected to produce the modulation signal. Fig. 2d shows the combination of the opposite phase filtered carrier C'' with the original wave. In this combination the phase of the carrier is reversed so that it combines with the side bands to form an AM wave which has an envelope 180 degrees out of phase with that fed to the other diode. The presence of this 180 degrees relation between the envelopes of the two modulated waves may be observed by noting that the side bands are rotated towards the minimum resultant amplitude point in Fig. 2c, and towards the maximum resultant amplitude point in Fig. 2d.

Thus, the differential combination of rectified voltages across diode resistors 14 and 15 is used to secure the detected phase modulations from both diodes. As stated before the AFC bias, available from the cathode end of resistor 14, is fed through the time constant circuit 16' to the control tube so that the carrier frequency is automatically maintained in tune with the crystal filter frequency. The latter is, of course, the operating I. F. value. Carrier exaltation is controlled by variable resistor 8 which is made higher in value to increase the carrier exaltation. The lower the magnitude of resistor 8 the less will be the degree of carrier exaltation. If desired, resistor 11 could be made variable to effect control over the degree of carrier exaltation. By "carrier exaltation" is meant the relative amplification of the carrier with respect to the sideband modulation components.

Referring now to the modification shown in Fig. 3, there is shown a demodulator network wherein a multi-grid detector tube is utilized in conjunction with a three-electrode crystal holder to provide a highly simplified form of PM detector. The I. F. energy is fed to the transformer 201 whose primary and secondary circuits are each resonated to the I. F. value. Each of the primary and secondary circuits has a damping resistor shunted thereacross to provide proper pass-band width. The third grid 210 of the detector tube 206 is connected to the high potential side of secondary circuit 201' of transformer 201. The piezo-electric crystal 202, which is tuned to the operating I. F. value, has three electrodes associated therewith. One of these electrodes is designated 203 and is connected to the low poten-

tial side of circuit 201'. The input electrode 205 is connected to the high potential side of the input circuit, while the output electrode 204 is connected to the first grid 211. The latter is connected back to ground through a grid return resistor, while the cathode of the detector tube is connected to ground through the usual carrier-bypassed biasing resistor 209. The plate 212 of the detector tube 206 is connected to a source of positive potential through the load resistor 207. The screen grid electrodes of tube 206 are connected to the positive terminal of the direct current voltage supply through a voltage reducing resistor 208.

It will be seen, therefore, that the input and output electrodes of the crystal filter are connected to respective grids 210 and 211 of the multi-grid detector tube. The demodulated output energy appears across the plate resistor 207 which is bypassed for the intermediate frequency by means of condenser 207'. AFC bias may also be taken from the plate end of resistor 207. Due to the fact that the plate of the detector tube has a permanent positive potential on it, the AFC bias obtained from the plate also has this permanent positive potential. This may be applied to a grid of the frequency control tube 212', if the cathode of the latter is made positive by an amount corresponding to the permanent voltage from the detector plate. In other words, the cathode of control tube 212' is connected to the positive potential source through resistor 211'.

The numeral 210' represents the bypassed cathode biasing resistor which is tapped at the proper point to provide a connection for the lower end of resistor R₁ thereby to apply the proper bias to first grid 213. Due to the phase shifter network C₁-R₁ connected to the plate, there is applied to grid 213 voltage which is in quadrature phase relation with voltage developed across the oscillator tank circuit (not shown). It will be understood that the plate of tube 212' is connected to the high alternating potential side of the tank circuit. In other words, the cathode-to-plate impedance of the control tube would be effectively connected across the oscillator tank circuit. This impedance will simulate a capacitive reactance, since the quadrature voltage for grid 213 is taken off across the resistive component of the phase shifter, and leads the voltage applied to the phase shifter since the phase shifter current leads the voltage. The AFC bias is fed through the time constant network 214 to the third grid 215, and the variation of its bias determines the magnitude of the plate-to-cathode impedance of tube 212'.

In one set of operating conditions a type 6L7 tube was used for tube 206; 800 ohms was the magnitude of resistor 209; and +250 volts were applied to the high voltage terminal at the junction of the resistors 207 and 208. With these conditions a positive potential of 50 volts appears at the plate of the detector tube. This amount of permanent potential may be easily compensated for by making the cathode of the reactance tube 50 volts more positive. This increases the current through cathode resistor 210' so as to make the cathode more positive than the end of resistor 207 to which the AFC line is connected.

The operation of the detector of Fig. 3 depends upon the combination of the filtered and unfiltered PM wave energy in the multi-grid detector tube. This combination is effected with a 90 degrees phase shift in the carrier, since the shielded three-electrode crystal filter inherently effects a

90 degrees phase change as the carrier is passed through it. More detailed description of the mode of operation of the multi-grid detector tube is disclosed in my aforesaid U. S. Patent No. 2,063,588.

The modification shown in Fig. 4 utilizes a four-electrode shielded crystal filter employed in conjunction with a detector of the type which has been disclosed in my application Serial No. 399,586, filed June 25, 1941. In this form of demodulator circuit the transformer 301 has its secondary circuit 301' arranged to be connected to the input electrodes 305 and 306 of the piezo-electric crystal filter which utilizes the crystal 302. The output electrodes 304 and 303 are connected to the plates 311' and 312' of respective rectifier tubes 311 and 312. The electrostatic shield 307 is employed to shield the input and output electrodes of the crystal filter.

The output load resistors 313 and 314 are connected in series between the cathodes of the rectifier tubes. The junction of the load resistors is connected to the junction of resistors 308 and 309. The latter resistors are arranged in series between plates 311' and 312'. The control grids of the rectifier tubes are connected in common to an adjustable tap 320. The latter is slideable along the resistor 310; the lower end of the latter is connected to a line connecting the junctions of resistors 313-314 and 308-309. The upper end of resistor 310 is connected through blocking condenser 310' and lead 315 to an adjustable contact 330. The latter may be connected either to the high potential side of input circuit 301' or to an AM contact arranged to be connected to the high potential side of the primary circuit of transformer 301. Thus, when the tap 330 is connected to the AM contact the demodulator tube is used for detection of AM waves. When it is connected as shown in Fig. 4 the circuit is utilized to demodulate PM wave energy.

It will now be seen that the filtered PM wave energy is fed directly to the plates of a pair of triode detectors 311 and 312. The unfiltered PM wave energy is fed through lead 315 and potentiometer 310-320 to the grids of the detectors. The degree of carrier exaltation may be adjusted by potentiometer slider 320. The detected modulation signal voltage and AFC bias appears across the differentially connected resistors 313 and 314. The load resistors are by-passed for I. F. currents.

The operation of the circuit shown in Fig. 4 depends upon the same principle as that shown in Fig. 3. However, in Fig. 4 the filtered and unfiltered energies are fed to the plate and grid of the triode detectors, instead of to separate grids of a multi-grid tube. The combination of energies takes place in the same manner, since in both types of detectors the detected output is obtained by virtue of the fact that the result is the product of the two signals applied to the two application points. That is, the arrangement of the electrodes in these tubes produces a condition such that the output is directly in proportion to the input in each one so that when voltages are applied to both, the output is proportional to the product of the two voltages.

As stated before the circuits shown in Fig. 4 may be converted for the reception of AM waves by connecting lead 315 to the primary circuit of transformer 301 instead of to the secondary. This makes use of the inherent phase shift of 90 degrees in the transformer so that the voltage fed to the two detector grids have the proper zero,

or 180 degrees, relationship for AM reception. There is an inherent 90 degrees phase shift between the input and output electrodes of the crystal filter. Hence, the two 90 degrees shifts are combined to form a zero, or 180 degrees, shift depending upon the polarity of the terminals of the transformer. The same mode of operation may be applied to the circuit of Fig. 3 in the same manner. With this amplitude modulation phase adjustment, AFC potentials must be obtained by another device, since the phase is not proper to produce them on the same detectors.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In combination with a source of phase modulated wave energy, a pair of opposed rectifiers having a common output circuit, a resonant circuit tuned to the mean frequency of the phase modulated energy, a piezo-electric crystal filter network having input electrodes connected to opposite sides of said resonant circuit and output electrodes connected to respective input electrodes of said rectifiers, said filter functioning to apply to said respective input electrodes substantially unmodulated energy of said mean frequency, and a condensive path free of any electron discharge device in shunt relation with said crystal filter for applying unfiltered phase modulated energy from high alternating potential side of said resonant circuit to said rectifiers.

2. In combination with a source of phase modulated wave energy, a converter network for converting the phase modulated energy to amplitude modulated energy, said network comprising a resonant circuit tuned to the mean frequency of the phase modulated energy, a piezo-electric crystal filter network having input terminals connected to opposite sides of said resonant circuit, a resistor network, said filter network having output terminals connected to spaced points of the resistor network, a path consisting of a condenser and resistor in series connected between the high potential side of said resonant circuit and an intermediate point of said resistor network for transmitting to the latter a portion of said phase modulated energy.

3. In combination with a resonant circuit to which is applied phase modulated carrier wave energy, a pair of piezo-electric crystal holders acting as input electrodes connected to opposite sides of said resonant circuit, a second pair of crystal holders acting as output electrodes, a pair of triode detectors having their anodes connected to respective ones of said output electrodes, means for connecting the control grids of said triodes

in common to the high potential side of said resonant circuit, and an output load resistor connected between the cathodes of the detector tubes.

4. In a modulated carrier wave detecting system, means for shifting the relative phase position of the carrier component of the modulated wave comprising, a piezo-crystal carrier filter in a four-electrode holder, two of said electrodes serving as input terminals, the other two serving as push-pull output terminals, and a coupling consisting of a condenser in series with an adjustable resistor from one of said input terminals to the midpoint of said push-pull output terminals.

5. In combination with a source of phase modulated wave energy, a pair of opposed rectifiers having a common output circuit, means for transforming the phase modulated energy to amplitude modulated energy comprising a circuit tuned to the center frequency of the phase modulated energy, a crystal filter network connected between said tuned circuit and respective input electrodes of said rectifiers, said filter functioning to apply to said respective input electrodes substantially unmodulated energy of said center frequency, a path in shunt with said crystal filter for applying unfiltered phase modulated energy from said tuned circuit to said rectifiers, said shunt path comprising a condenser in series with an adjustable resistor.

6. In combination with a source of phase modulated wave energy, a network for converting the phase modulated energy to amplitude modulated energy, said network comprising a resonant circuit tuned to the mean frequency of the phase modulated energy, a crystal filter having a pair of input electrodes connected to opposite sides of said resonant circuit, said filter having a pair of output electrodes, a resistor network connected between the output electrodes, a path comprising a condenser in series with a resistor connected between the high potential side of said resonant circuit and an intermediate point of said resistor network for transmitting to the latter phase modulated energy.

7. In combination with a resonant circuit to which is applied phase modulated carrier wave energy, a pair of piezo-electric crystal holders acting as input electrodes connected to opposite sides of said resonant circuit, a second pair of crystal holders acting as output electrodes, a pair of triode detectors having their anodes connected to respective ones of said output electrodes, means for connecting the control grids of said triodes in common to the high potential side of said resonant circuit, an output load resistor connected between the cathodes of the detector tubes, and additional means for selectively disconnecting the grids from the resonant circuit and connecting them to a wave energy point prior to the resonant circuit.

MURRAY G. CROSBY.
